Primary Examiner — Terry A Wallace(74) *Attorney, Agent, or Firm* — Rankin, Hill & Clark LLP(57) **CLAIM**

The ornamental designs for an combined insulated bottle and lid, as shown, and described.

DESCRIPTION

FIG. 1 is a perspective view of an combined insulated bottle and lid;

FIG. 2 is a front elevation view thereof (with the rear a mirror image thereof);

FIG. 3 is a right elevation view thereof (with the left a mirror image thereof);

FIG. 4 is a top view thereof; and,

FIG. 5 is a bottom view thereof.

The broken lines in the drawings depict portions of the combined insulated bottle and lid that form no part of the claimed design.
